UNITED STATES PATENT OFFICE.

WILLIAM S. HALSEY, OF PITTSBURG, PENNSYLVANIA.

RATCHET-DRILL.

SPECIFICATION forming part of Letters Patent No. 663,887, dated December 18, 1900.

Application filed August 30, 1900. Serial No. 28,510. (No model.)

To all whom it may concern:

Be it known that I, WILLIAM S. HALSEY, of Pittsburgh, in the county of Allegheny and State of Pennsylvania, have invented a certain new and useful Improvement in Ratchet-Drills, of which improvement the following is a specification.

The object of my invention is to improve the construction and perfect the operation of a ratchet-drill of the construction ordinarily employed in machine-work by the provision of simple, inexpensive, and self-contained means for effecting the self or automatic feed of the drill to the work.

15 The improvement claimed is hereinafter fully set forth.

In the accompanying drawings, Figure 1 is a view, partly in elevation and partly in section, of a ratchet-drill, illustrating an application of my invention; and Fig. 2, a transverse section at the line *x x* of Fig. 1.

My invention is herein exemplified as applied in connection with a ratchet-drill having, as in ordinary practice, a drill-spindle 1, 25 provided with a central socket 2 at one of its ends, in which a drill 3 is suitably secured. The drill-spindle is fitted to rotate in or with, as the case may be, the jaws 4 of a drill-stock or operating-handle 5 and has secured upon 30 it a ratchet-wheel 6, the teeth of which are engaged by a pawl 7, pivoted to the jaws 4. An internal thread 8, which forms a feed-nut, is cut centrally in the drill-spindle 1, extending from the end thereof opposite that in 35 which the socket 2 is formed for a distance proportionate to the desired range of longitudinal feed to be imparted to the drill, its inner end being, in the instance shown, located near the axial plane of the drill-stock 5.

40 A feed-screw 9, having a conical center 10 on its outer end to abut against a fixed support, engages the feed-nut 8, its outer end projecting therefrom sufficiently far to enable it to be connected, as by a pin 11, to a feed-screw sleeve 12, which fits truly on the periphery of the drill-spindle and has a long bearing thereon, preferably extending to or near the adjacent jaw 4 of the drill-stock. In order to admit of independent hand-feed, if desired, 45 the feed-screw 9 and feed-screw sleeve 12 may be connected by a pin 13, passing through one

of a series of transverse passages 14 in the sleeve and through a passage at right angles thereto in the feed-screw.

A friction-sleeve 15, which is partially split 55 or divided by a longitudinal passage 16 on one side and is formed upon or fixed to the jaw 4 on the side of the drill-stock adjacent to the feed-screw, fits freely around the feed-screw sleeve 12 and is provided with an annular recess near its outer end, in which is fitted a friction-ring 17, of wood, vulcanite fiber, leather, or other suitable material. A clamping-bolt 18 passes through lugs 19 on each side of the longitudinal passage 16 and 60 serves to draw the sides of said passage toward each other and to thereby effect the operative connection of the friction-sleeve 15 and feed-screw sleeve 12 through the induced compression and frictional contact with said 65 sleeves of the friction-ring 17.

It will be apparent to those skilled in the art that the relative external and internal positions of the feed-nut 8 and feed-screw 9, respectively, are not essentials of my invention 75 and that they may be reversed, if desired, without departure from the essential features or operative principle thereof—that is to say, the feed-nut may be formed as an internal thread on the sleeve 12 and the feed-screw as 80 an external thread on the drill-spindle 1. The operation of the device will be the same in all particulars with such reversal of position as in the specific embodiment of my invention shown in the drawings, and I therefore specify a construction in which it is presented as the mechanical equivalent of that specifically herein described and shown.

In the operation of the drill, the clamping-bolt 18 having been screwed up to induce 90 proper frictional contact of the ring 17 and sleeves 15 and 12, the stock 5 is turned in the direction for forward or working movement of the drill 3, which is imparted thereto through the engagement of the pawl 7 and 95 ratchet 6, all the members of the appliance moving coincidently in this stroke of the drill-stock. When the stock has made the full traverse which is admissible under the conditions of the work, it is turned backward in 100 the usual manner preparatory to its succeeding working stroke. In the backward trav-

erse of the stock the pawl 7 slips over the teeth of the ratchet-wheel 6, and no rotative movement is imparted to the drill-spindle 1 and drill 3. The feed-screw 9 is, however, 5 rotated with the stock through its positive connection with the feed-screw sleeve 12 and the frictional engagement of the sleeves 12 and 15 through the friction-ring 17. The rotation of the feed-screw consequently imparts 10 longitudinal movement to the then non-rotating feed-nut 8, by which the connected drill 3 is automatically fed into the work during the backward stroke of the drill-stock 5.

My improvement presents the substantial 15 advantages of simplicity of construction, effective operative capacity, and inconsiderable cost, and being wholly self-contained it may be used within a limited space where the extraneous appliances heretofore employed for effecting self feed would not be practicable. The economy effected in dispensing with such extraneous feed devices 20 will be apparent to the skilled mechanic.

I claim as my invention and desire to secure 25 by Letters Patent—

1. In a ratchet-drill, the combination of a drill-spindle, a drill connected thereto, a drill-stock, means for imparting rotative movement from the drill-stock to the drill-spindle, 30 in one direction only of traverse of the drill-stock, a feed-nut in the drill-spindle, a feed-screw engaging said nut, a member connected to and movable with the feed-screw and having a frictional surface, a member connected 35 to and movable with the drill-stock and having an adjoining frictional surface, and

means for bringing said frictional surfaces into operative frictional contact.

2. In a ratchet-drill, the combination of a drill-spindle, a drill connected thereto, a drill- 40 stock, means for imparting rotative movement from the drill-stock to the drill-spindle, in one direction only of traverse of the drill-stock, a feed-nut in the drill-spindle, a feed- screw engaging said nut, a sleeve secured to 45 the feed-screw, a friction-ring surrounding said sleeve, and connected with the drill- stock, and a clamping device adapted to induce and maintain operative frictional contact between the friction-ring and the feed- 50 screw sleeve.

3. In a ratchet-drill, the combination of a drill-spindle, a drill connected thereto, means for imparting rotative movement from the drill-stock to the drill-spindle, in one direction only of traverse of the drill-stock, a feed- 55 nut formed centrally in the drill-spindle, a feed-screw engaging said nut and having a center on its outer end, a sleeve fixed to the feed-screw and fitting freely on the drill- spindle, a split or divided sleeve fixed to the drill-stock and fitting around the feed-screw sleeve, a friction-ring held in a recess in the drill-stock sleeve and fitting the periphery of the feed-screw sleeve, and a clamping- 60 screw engaging the divided portion of the drill-stock sleeve and acting to compress the friction-ring against the feed-screw sleeve. 65

WILLIAM S. HALSEY.
